FIG. 1

FIG. 3

COVER WITH ADJUSTABLE WIDTH

CROSS REFERENCE TO RELATED APPLICATIONS

This is a U.S. National Stage Application of, and claims the benefit to, PCT/GB2020/051682, filed Jul. 13, 2020, which claims priority to United Kingdom patent application s/n GB 1910947.9, filed Jul. 31, 2019, the contents of each is incorporated herein by reference in its entirety.

This disclosure relates to a cover for covering an opening, in particular an opening in a floor. This disclosure also relates to a method of covering an opening and a kit of parts for forming the cover.

BACKGROUND

Covers for covering openings are known. For garage inspection pits, the applicant's prior patent GB2472798 discloses one suitable cover. Typically, the cover is manufactured for a given garage inspection pit and installed in-place on site. The cover is formed from a parallel array of longitudinal members laterally spaced in a planar arrangement, with two pantograph arrangements pivotably connected to each of the longitudinal members, allowing the cover length to be varied. Access to the garage inspection pit can be provided by contracting the cover, or by removing the cover entirely. Access to the garage inspection pit can be at least partially prevented by providing the cover over the opening, and/or expanding the cover from the contracted position to cover the opening.

It is in this context that the present invention has been developed.

BRIEF SUMMARY OF THE DISCLOSURE

In accordance with the present disclosure there is provided a cover for covering an opening defined in a surface. The opening is defined between a first edge and a second edge. The first edge and the second edge define an opening width therebetween, shorter than a length of the opening. The cover has a cover width and is configured to be supported, in use, at the first edge and the second edge of the opening when the cover width is parallel to the opening width. The cover width is adjustable from a first cover width to a second cover width. The cover is configured to maintain the cover width at the second cover width, in use.

Thus, there is provided a cover, sometimes referred to as an access panel, which can be suitable for installation in openings of different widths. Previously, covers were manufactured to order to specific opening sizes. It will be understood that the cover is particularly of use where the openings are for garage inspection pits, sometimes referred to as vehicle inspection pits. The cover may be for fully covering the opening. The cover may be for partially covering the opening.

The cover may be configured to substantially permanently prevent adjustment of the cover width to the first cover width after activation of a retaining mechanism when the cover width is at the second cover width. Thus, after installation of the cover in the opening, the width of the cover cannot be changed. This ensures that the width of the cover is not accidentally shortened in width, allowing the cover to fall through the opening. Thus, the safety of the cover is improved. Activation of the retaining mechanism may be insertion of a retaining fastener through a retaining opening

and penetration into the cover, to substantially prevent widthways expansion or contraction of the cover.

The cover may comprise a plurality of parallel members, each arranged to be provided between the first edge and the second edge of the opening. Each of the plurality of parallel members may be arranged to be extensibly connected to an adjacent parallel member of the plurality of parallel members. Thus, a length of the cover is adjustable. The parallel members may be extensibly connected in a lengthways direction, sometimes referred to as a longitudinal direction. Thus, the cover can vary in length in a particularly efficient manner, being relatively easy to manufacture and operate.

The plurality of parallel members may be connected via a pantograph linkage, sometimes referred to as a scissor mechanism, with each of the parallel members connected at a crossing point of the linkage, sometimes referred to as at an "X" of the linkage.

Each of the plurality of parallel members may be provided with at least one telescopic extension arm, configured to be 20 slidably received in the parallel member to adjust the cover width from the first cover width to the second cover width. Thus, the cover can vary in width in a particularly efficient manner, being relatively easy to manufacture and operate during installation.

25 Of the plurality of parallel members and the at least one telescopic extension arm for each of the plurality of parallel members, in some embodiments, only the plurality of parallel members has defined therein an opening for receiving a retaining fastener to retain the cover width at the second 30 cover width. In other words, the retaining fastener will need to be of a self-tapping type to penetrate through the telescopic extension arms as no opening is provided there. Advantageously, this ensures that a continuum of widths can be chosen, ensuring that the best possible fit of the cover to 35 the opening is achievable. In other words, the width of the cover is not chosen from a limited, discrete plurality of possible options. The retaining fastener may be a self-tapping screw. The cover may comprise the retaining fastening.

40 Each of the plurality of parallel members may comprise two telescopic extension arms, one each extending from each of a first end and a second end of the respective parallel member. Thus, the plurality of parallel members can remain substantially centralised in the opening, and the length of the 45 telescopic extension arms used to transmit any load from the parallel members to the edges of the opening can be reduced.

The cover may further comprise an extension stop moveable with at least one of the telescopic extension arms of the plurality of parallel members. The extension stop is configured to substantially prevent extension of at least one other of the telescopic extension arms of the plurality of parallel members beyond the at least one of the telescopic extension arms. Thus, during installation of the cover in the opening, the extension stop can make it easier to ensure all of the telescopic extension arms are at substantially the same extension.

The cover may further comprise movement means for facilitating movement of at least a portion of the cover at the first edge and the second edge of the opening. The movement means may be a skid, such as a relatively low-friction skid, for example a plastics skid. Alternatively, the movement means may be wheels or substantially any other component or surface treatment for ensuring easy movement of the cover relative to the edges of the opening.

65 The cover may be for covering a vehicle inspection pit. The vehicle inspection pit is sometimes referred to as a garage inspection pit.

The present disclosure extends to a method of covering an opening defined between a first edge and a second edge. The first edge and the second edge define a predetermined opening width therebetween. The method comprises: providing a cover, as described hereinbefore, at the opening; adjusting a cover width of the cover from a first cover width to a second cover width, the second cover width corresponding to the predetermined opening width such that the cover can cover the opening; and maintaining the cover width at the second cover width, in use. The second cover width may be greater than the first cover width. The method may comprise substantially permanently maintaining the cover width at the second cover width, in use.

When the cover comprises the plurality of parallel members and at least one telescopic extension arms, as described hereinbefore, the method may further comprise: affixing an extension stop to at least one of the telescopic extension arms of the plurality of parallel members, the extension stop moveable with the at least one of the telescopic extension arms, and configured to substantially prevent extension of at least one other of the telescopic extension arms of the plurality of parallel members beyond the at least one of the telescopic extension arms; extending the at least one other of the telescopic extension arms of the plurality of parallel arms to abut against the extension stop; securing the telescopic extension arms relative to the plurality of parallel members. The method may further comprise removing the extension stop from the at least one of the telescopic extension arms. Thus, the cover can be easily installed in an opening.

The present disclosure extends to a kit of parts for forming a cover for an opening defined in a surface, the opening defined between a first edge and a second edge. The first edge and the second edge define a predetermined opening width therebetween, shorter than a length of the opening. The kit of parts comprises: a cover as described hereinbefore; and one or more retaining fasteners for engaging with the cover to maintain the cover width at the second cover width.

The kit of parts may further comprise an extension stop moveable with at least one of the telescopic extension arms of the plurality of parallel members, the extension stop configured to substantially prevent extension of at least one other of the telescopic extension arms of the plurality of parallel members beyond the at least one of the telescopic extension arms.

The surface may be a ground surface. A maximum width of the cover may be less than 5 metres. A maximum width of the cover may be less than 2 metres. A minimum width of the cover may be greater than 50 centimetres. A maximum length of the cover may be less than 10 metres. A minimum length of the cover may be greater than 10 centimetres. A minimum length of the cover may be less than 1 metre.

BRIEF DESCRIPTION OF THE DRAWINGS

Embodiments of the invention are further described hereinafter with reference to the accompanying drawings, in which:

FIG. 1 is an illustration of a cover as disclosed herein;

FIG. 2 is an illustration of a portion of the cover shown in FIG. 1;

FIG. 3 is an illustration of a feature of the cover shown in FIGS. 1 and 2, used during installation of the cover

FIG. 4 is an illustration of the cover shown in FIGS. 1 to 3, in use for covering an opening; and

FIG. 5 is an illustration of an example of a cover as disclosed herein.

DETAILED DESCRIPTION

FIG. 1 is an illustration of a cover as disclosed herein. The cover 10 is for covering an opening defined in a surface. Typically, the opening is a substantially horizontal opening. The cover is generally sufficiently strong to support the weight of a person, and/or a vehicle, and/or maintenance equipment. In this way, the safety hazard presented by the presence of the opening in the surface (through which a person or equipment could fall) is reduced or even completely negated. Sometimes, it will be understood that access to a void defined beyond the opening in the surface is required. The cover 10 can be removed to allow access to the void. In some examples, the cover 10 can be partially compressed to remove the cover 10 from a portion of the opening, without complete removal of the cover 10 from the opening. The use of the cover 10 is further described with reference to FIG. 4 hereinafter. In FIG. 1, the cover 10 is viewed from a top, with the cover 10 for use in covering an opening the other side of the cover 10.

The cover 10 defines a cover width W_c and a cover length L_c . The cover 10 is adjustable in a length direction between a collapsed configuration in which the cover length L_c is substantially at a minimum and an expanded configuration in which the cover length L_c is substantially at a maximum. As necessary, the presently described cover 10 may be provided in substantially any position between the collapsed configuration and the expanded configuration. In FIG. 1, the cover 10 is shown in a position between the collapsed configuration and the expanded configuration. Thus, the cover 10 can be adjusted in length to cover a number of different proportions of the opening. The cover 10 of the present disclosure is also adjustable in width between a first cover width and a second cover width. In this way, it will be appreciated (as will be explained further hereinafter) that the same cover 10 can be installed in either an opening of a first width, or with an opening of a second width, different from the first width.

The specific cover 10 disclosed herein comprises a plurality of parallel members 20, 20a, 20b, 20c, 20d, 20e, 20f, 20g, 20h, 20i. The plurality of parallel members 20, 20a, 20b, 20c, 20d, 20e, 20f, 20g, 20h, 20i are each arranged to be extensibly connected to adjacent parallel members 20a, 20b, 20c, 20d, 20e, 20f, 20g, 20h, 20i of the plurality of parallel members 20, to allow adjustment of the length of the cover 10. In this example, the plurality of parallel members 20, 20a, 20b, 20c, 20d, 20e, 20f, 20g, 20h, 20i are extensibly connected by an extension unit 30, 32, in the form of a first pantograph linkage 30 and a second pantograph linkage 32. The pantograph linkages 30, 32 are each pivotably linked to each of the plurality of parallel members 20, 20a, 20b, 20c, 20d, 20e, 20f, 20g, 20h, 20i. In this way, it can be seen that the pantograph linkages 30, 32, ensure that the plurality of parallel members 20, 20a, 20b, 20c, 20d, 20e, 20f, 20g, 20h, 20i remain equally spaced and parallel during adjustment of the length of the cover 10.

Each of the plurality of parallel members 20, 20a, 20b, 20c, 20d, 20e, 20f, 20g, 20h, 20i is provided with at least one telescopic extension arm, in this example a first telescopic extension arm 22a, 22b, 22c, 22d, 22e, 22f, 22g, 22h, 22i and a second telescopic extension arm 24a, 24b, 24c, 24d, 24e, 24f, 24g, 24h, 24i. For ease of explanation, among the plurality of parallel members 20, 20a, 20b, 20c, 20d, 20e, 20f, 20g, 20h, 20i, the second parallel member 20b will be

described further below, but it will be understood that the description and explanation applies equally to any of the other parallel members with relevant changes to the reference numerals as appropriate.

The first telescopic extension arm **22b** for the second parallel member **20b** is telescopically received within the second parallel member **20b**. In other words, the second parallel member **20b** defines an open first end of sufficient size to receive the first telescopic extension arm **22b** therein. Similarly, the second telescopic extension arm **24b** for the second parallel member **20b** is telescopically received within the second parallel member **20b**, at an opposite end of the second parallel member **20b** to the first telescopic extension arm **22b** received therein. In other words, the second parallel member **20b** further defines an open second end, opposite the open first end, of sufficient size to receive the second telescopic extension arm **24b** therein. As will be described further with reference to FIG. 2 hereinafter, the second parallel member **20b** also defines a portion of a retaining mechanism in the form of a first retaining opening and a second retaining opening, each defined in the second parallel member **20b**, and arranged to receive a retaining fastener therein to engage with the telescopic extension arms **22b**, **24b** to substantially prevent further telescopic movement thereof relative to the second parallel member **20b**. In this way, the cover **10** can be fixed in width during installation.

The cover **10** further comprises a locking mechanism **40** to reduce or even substantially prevent accidental adjustment of the length and longitudinal positioning of the cover **10** when covering the opening. In this example, the locking mechanism **40** is provided at each side of the first parallel member **20a** and the ninth parallel member **20i**, mounted to the first and second telescopic extension arms **22b**, **24b**, thereof. The functioning of the locking mechanisms **40** will be described further with reference to FIG. 2 hereinafter.

FIG. 2 is an illustration of a portion of the cover **10** shown in FIG. 1. In particular, FIG. 2 shows a first parallel member **20a** having a first telescopic extension arm **22a** extending telescopically therefrom. In FIG. 2, the first parallel member **20a** is viewed from a side-on direction. It will be understood that the first parallel member **20a** is as described hereinbefore, and extends further than shown in FIG. 2. The first parallel member **20a** is cut-off show that a greater amount of detail can be presented in the remaining components of the cover **10**. The cover **10** is shown in-place covering an opening **O** defined between a first edge **110** and a second edge (not shown). As can be seen, typically the first edge **110** of the opening is provided with a first side-wall **112**, a lip region **114** and a second side-wall **116**. The first side-wall **112** and the second side-wall **116** are each substantially vertical and are connected via the lip region **114**, arranged to be substantially horizontal. The opening **O** is ultimately defined within a ground surface **120**. In this example, there are a plurality of locating openings **118** defined in the first side-wall **112**. It will be understood that in other examples locating openings **118** may be provided elsewhere, such as in the lip region **114**, or may even not be provided at all.

As described hereinbefore, the first telescopic extension arm **22a** extending from the first parallel member **20a** is provided with a locking mechanism **40**. The locking mechanism **40** comprises a sliding bolt **42**, biased outwards by a biasing mechanism **44**, such as a spring **44**. A tip **46** of the sliding bolt **42** is arranged to be receivable within the locating openings **118** in the first side-wall **112** of the opening **O**. In this example, the locking mechanism **40** further comprises a handle **48**, provided at an end of the

sliding bolt **42**, opposite the tip **46**, for retracting the sliding bolt **42** against the restoring action of the biasing mechanism **44**. Where the locating openings **118** are provided in the lip region, it will be understood that the locking mechanism **40** may instead comprise a pin arranged to extend into a locating opening in the lip region; in other words, for a horizontal opening **O**, the pin may be a vertical pin extending downwards from a lower surface of the telescopic extension arm **22a**.

As can be seen in FIG. 2, in this configuration, an extension of the first telescopic extension arm **22a** from the first parallel member **20a** has been fixed by activation of a retaining mechanism **50**. The retaining mechanism **50** in the present example is activated by insertion of a retaining fastener **52** through a first retaining opening **54** defined in the first parallel member **20a**. The retaining fastener **52** can be in the form of a self-tapping screw, arranged to penetrate into the first telescopic extension arm **22a**, thereby securing the first telescopic extension arm **22a** relative to the first parallel member **20a**. A broken line representation is used in FIG. 2 to convey that the first telescopic extension arm **22a** extends within the first parallel member **20a**. Thus, the configuration of the cover **10** shown in FIG. 2 is when the cover is already installed in the opening **O**.

An underside of the first telescopic extension arm **22a** is provided with movement means **60**, for example in the form of a skid member **60**, to facilitate easy movement of the cover **10** relative to the opening, and in particular, easy movement of the first telescopic extension arm **22a** longitudinally along the lip region **114**. The skid member **60** may be provided by a low-friction material, for example a plastics material, configured to allow easy manipulation of the cover **10** around the opening **O**.

It will be understood that other parallel members of the plurality of parallel members, as well as the other end of the first parallel member **20a** may be substantially as described above in relation to the first parallel member **20a**, though parallel members not being at the outermost edges of the cover **10** (in this example the first parallel member **20a** and the ninth parallel member **20i**) typically will not be provided with the locking mechanism **40**.

FIG. 3 is an illustration of a feature of the cover shown in FIGS. 1 and 2, used during installation of the cover. In other words, FIG. 3 shows the cover **10** prior to installation in the opening **O**, described with reference to FIG. 2 hereinbefore. The cover **10** is provided in the collapsed configuration, where the cover length **L_c** is substantially at a minimum. An extension stop member **70** is provided to substantially prevent extension of any of the first telescopic extension arms **22a**, **22b**, **22c**, **22d**, **22e**, **22f**, **22g**, **22h**, **22i** beyond at least one of any telescopic extension arms **22a**, **22i** connected to the extension stop member **70**. As will be appreciated, FIG. 3, as in FIG. 2, shows only one portion of the cover **10**, and substantially similar provisions can be provided on the other end of the cover **10**, with a further extension stop member (not shown) for the second telescopic extension arms **24a**, **24b**, **24c**, **24d**, **24e**, **24f**, **24g**, **24h**, **24i**. In this example, the extension stop member **70** is in the form of an L-bracket, secured to at least one (in this example two) of the first telescopic extension arms. In this example, the extension stop member **70** is secured to the first telescopic extension arms **22a**, **22i** of the first parallel member **20a** and the ninth parallel member **20i**. A vertical portion of the L-bracket providing the extension stop member **70** ensures that none of the first telescopic extension arms **22a**, **22b**, **22c**, **22d**, **22e**, **22f**, **22g**, **22h**, **22i** can extend beyond the extension stop member **70**. Advantageously, this makes it

easy for the length of extension of the first telescopic extension arms 22a, 22b, 22c, 22d, 22e, 22f, 22g, 22h, 22i from the plurality of parallel members 20 to be set uniformly. Once a telescopic extension arm is in the correct extension position, the extension position can be maintained by activation of the retaining mechanism, for example using retaining fasteners through the retaining openings 54, substantially as described with reference to FIG. 2 hereinbefore. After the retaining mechanisms have been activated, the extension stop member 70 can be removed from the cover 10. In examples where the extension stop member 70 was secured to more than one of the telescopic extension arms, removal of the extension stop member 70 can subsequently allow the cover length L_c to be altered as necessary to cover more or less of the opening O. A further benefit of the L-bracket design of the extension stop member 70 is that when the cover is located in the opening and the extension stop member 70 expanded to abut directly against the edges of the opening prior to securing the telescopic extension arm in position by activation of the retaining mechanism, on subsequent removal of the extension stop member 70 from the cover 10, a suitable tolerance will remain between an edge of the telescopic extension arms and the edges of the opening O to ensure smooth movement of the cover 10 within the opening.

FIG. 4 is an illustration of the cover shown in FIGS. 1 to 3, for covering an opening, in use. A first cover 10a and a second cover 10b, each substantially the same as the covers described hereinbefore with reference to FIGS. 1 to 3, are shown in-place partially covering an opening O defined between a first edge 110 and a second edge 120. The first edge 110 and the second edge 120 define an opening width W_o therebetween. The opening also defines an opening length L_o , longer than the opening width W_o . It will be understood that, typically, length is transverse to width. As can be seen, the covers 10a, 10b are each configured to be supported, in use, at the first edge 110 and the second edge 120 of the opening when the cover width W_c is parallel to the opening width W_o . As described hereinbefore, the cover width W_c is adjustable from a first cover width to a second cover width, during installation of the cover 10a, 10b in the opening, such that the cover 10a, 10b is configured to maintain the cover width W_c at the second cover width, in use. In the arrangement shown in FIG. 4, it will be understood that complete coverage of the opening O can be achieved by extension of either or both of the first cover 10a and the second cover 10b in the length direction. Access to one end of the opening O can be provided either by removal of one or both of the covers 10a, 10b, or alternatively by movement of the covers 10a, 10b to an opposite end of the opening O, in the lengthwise direction, and by contraction of the covers 10a, 10b into their collapsed configuration, as described hereinbefore. The position and lengthwise extension of the covers 10a, 10b can be maintained via use of the locking mechanisms 40, as described hereinbefore.

FIG. 5 is an illustration of an example of a cover as disclosed herein. The cover 210 is substantially similar in form and function to the covers described hereinbefore, apart from any hereinafter noted differences. The cover 210 includes ten parallel members, instead of the nine parallel members shown in the covers of FIGS. 1 to 4. The parallel members of the cover 210 of FIG. 5 also include two retaining openings for each of the telescopic extension arms. When retaining fasteners are engaged with a telescopic extension arm through both of the retaining openings, this improves a stability of the cover 210, when installed. It will be understood that an outer extent of a cross-section of the

telescopic extension arms must be smaller than an inner extent of a cross-section of the parallel members to facilitate telescopic movement of the telescopic extension arms therein. Typically, without securing the telescopic extension arm relative to the parallel member using two retaining fasteners, slight movement of the telescopic extension arm may still occur, which would decrease the stability, or at least the apparent stability of the cover 210. A further benefit is that use of two retaining fasteners provide redundancy in the highly unlikely event of failure of one of the retaining fasteners.

It will be understood that the cover 10 described hereinbefore may be formed from any suitable material and in any suitable length, width or other sizes as necessary to provide a cover for covering an opening in a surface. In at least some examples, it will be important that the cover 10 is able to support a person, or even heavier loads such as a vehicle, thereon.

Although the present disclosure has described a cover for covering an opening of a garage inspection pit, sometimes referred to as a vehicle inspection pit, it will be understood that the cover can also be used to cover any other type of opening, for example openings where the width of the opening can vary between different openings, by design or manufacturing tolerance.

Throughout the description and claims of this specification, the words "comprise" and "contain" and variations of them mean "including but not limited to", and they are not intended to (and do not) exclude other components, integers or steps. Throughout the description and claims of this specification, the singular encompasses the plural unless the context otherwise requires. In particular, where the indefinite article is used, the specification is to be understood as contemplating plurality as well as singularity, unless the context requires otherwise.

Features, integers, characteristics or groups described in conjunction with a particular aspect, embodiment or example of the invention are to be understood to be applicable to any other aspect, embodiment or example described herein unless incompatible therewith. All of the features disclosed in this specification (including any accompanying claims, abstract and drawings), and/or all of the steps of any method or process so disclosed, may be combined in any combination, except combinations where at least some of such features and/or steps are mutually exclusive. The invention is not restricted to the details of any foregoing embodiments. The invention extends to any novel one, or any novel combination, of the features disclosed in this specification (including any accompanying claims, abstract and drawings), or to any novel one, or any novel combination, of the steps of any method or process so disclosed.

The invention claimed is:

1. An inspection pit cover for covering an inspection pit opening defined in a surface and adapted to support a person, the opening defined between first and second edges, and an opening width defined between the first and second edges that is shorter than a length of the opening, the inspection pit cover comprising:

a cover width, wherein the inspection pit cover is configured to be supported, during use, at the first and second edges of the opening when the cover width is substantially parallel to the opening width, wherein the cover width is adjustable from a first cover width to a second cover width, and the cover is adapted to maintain the cover width at the second cover width during use;

parallel members, each of the parallel members is arranged to be provided between the first and second edges of the opening, and extensibly connected to an adjacent parallel member of the parallel members, such that a length of the cover is adjustable, wherein the parallel members respectively include telescopic extension arms that are adapted to be slidably received in the respective parallel members to adjust the cover width from the first cover width to the second cover width; retaining mechanisms respectively provided on the parallel members and configured to maintain the cover width at the second cover width, wherein the retaining mechanisms are respectively defined by retaining openings respectively receiving retaining fasteners, and each retaining opening is defined by only the respective parallel member; and

wherein the retaining fasteners engage each of the telescopic extension arms to substantially permanently prevent adjustment of the cover width to the first cover width after activation of the retaining mechanisms when the cover is at the second cover width.

2. The inspection pit cover as claimed in claim 1, wherein each of the parallel members includes two of said telescopic extension arms, one each of the telescoping extension arms extending from each of a first end and a second end of the respective parallel member.

3. The inspection pit cover as claimed in claim 1, further comprising an extension stop moveable with at least one of the telescopic extension arms, the extension stop is adapted to substantially prevent extension of at least one of the other of the telescopic extension arms beyond the at least one of the telescopic extension arms which is moveable with the extension stop.

4. The inspection cover as claimed in claim 1, wherein the inspection pit cover is adapted to cover a vehicle inspection pit.

5. A method of covering an inspection pit opening defined between a first edge and a second edge, and defining a predetermined opening width therebetween, the method comprising:

providing an inspection pit cover as claimed in claim 1 at the opening;
adjusting a cover width of the cover from a first cover width to a second cover width, the second cover width

corresponding to the predetermined opening width such that the cover can cover the opening; and maintaining the cover width at the second cover width, in use.

6. A method as claimed in claim 5, further comprising: affixing an extension stop to at least one of the telescopic extension arms, the extension stop moveable with the at least one of the telescopic extension arms, and adapted to substantially prevent extension of at least one of the other of the telescopic extension arms beyond the at least one of the telescopic extension arms which is moveable with the extension stop; extending the at least one other of the telescopic extension arms to abut against the extension stop; securing the telescopic extension arms relative to the parallel members; and removing the extension stop from the at least one of the telescopic extension arms.

7. A kit for forming a cover for an inspection pit opening defined in a surface, the opening defined between a first edge and a second edge, and defining a predetermined opening width therebetween, shorter than a length of the opening, the kit of parts comprising:

a cover as claimed in claim 1; and the retaining fasteners for being received in the retaining openings and engaging with the cover to maintain the cover width at the second cover width.

8. The kit of parts as claimed in claim 7, further comprising an extension stop moveable with at least one of the telescopic extension arms, the extension stop adapted to substantially prevent extension of at least one other of the telescopic extension arms beyond the at least one of the telescopic extension arms which is moveable with the extension stop.

9. The inspection pit cover as claimed in claim 1, further comprising a skid for facilitating movement of at least a portion of the cover at the first edge and the second edge of the opening.

10. The inspection pit cover as claimed in claim 1, further comprising one or more wheels for facilitating movement of at least a portion of the cover at the first edge and the second edge of the opening.
